(57) **CLAIM**

The ornamental design for a “monitor adapter”, substantially as shown and described.

DESCRIPTION

FIG. 1 is a front, top, and right side perspective view of a monitor adapter, showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.
